UNITED STATES PATENT OFFICE.

WILLIAM H. BEVANS, OF WASHINGTON, DISTRICT OF COLUMBIA.

SEMI-AUTOMATIC BREECH-LOADING ORDNANCE.

SPECIFICATION forming part of Letters Patent No. 703,375, dated July 1, 1902.

Application filed January 9, 1900. Serial No. 847. (No model.)

To all whom it may concern:

Be it known that I, WILLIAM H. BEVANS, a citizen of the United States, residing at Washington, in the District of Columbia, have invented certain new and useful Improvements in Semi-Automatic Breech-Loading Ordnance; and I do hereby declare the following to be a full, clear, and exact description of the invention, such as will enable others skilled in the art to which it appertains to make and use the same.

This invention relates generally to improvements in breech-loading ordnance, and particularly to that class known as "semi-automatic," the object being to provide an improved construction to be applied to breech-loading guns for the purpose of utilizing the energy of recoil of the gun to cock the hammer, open the breech, extract the cartridge-case, and when tripped automatically by the insertion of a fresh cartridge or by hand to return the breech-block to its position, closing the breech.

The special features of my invention are its simplicity, its adaptability with slight modifications to breech-loading ordnance having differently-constructed breech mechanisms, it being not limited to guns having transversely-movable blocks, as illustrated in the present instance, but may be used with other forms of breech mechanisms wherein the block swings to open the breech or moves longitudinally.

Another important feature of the invention is that it may be applied to guns already in use, thus making the same automatic.

In the accompanying drawings, Figure 1 is a side elevation of a portion of a gun provided with my invention, the parts being in their normal positions. Fig. 2 is a similar view with the gun omitted, showing the positions of the parts when the gun has reached the limit of its recoil. Fig. 3 is a view similar to Fig. 2, showing the positions of the parts when the gun has returned to firing position and the breech-block has been moved to open the breech. Fig. 4 is an enlarged sectional view through one of the walls of the gun-breech and the crank-shaft operating mechanism. Figs. 5 and 6 are detail views of the plunger for locking the crank-arm and spring-cylinder together. Fig. 7 is a side ele-

vation of a modified construction. Fig. 8 is a horizontal section through the gun-breech, showing the construction for automatically releasing the spring-cylinder from the crank-arm. Figs. 9, 10, and 11 are sectional views showing the operation of the parts in automatically disengaging the cylinder from the crank-arm. Fig. 12 is a perspective view of the locking-plunger. Fig. 13 is a detached view of the false extractor and its actuating means.

The gun here illustrated is provided with the common form of breech mechanism known as the "Hotchkiss breech mechanism," some of the parts having been removed in the application of my invention, and said mechanism forms no part of my present invention.

The Hotchkiss mechanism, briefly stated, consists of a drop-block which is adapted to be moved transversely of the axis of the gun by a crank A on a shaft B, which projects to the exterior of the gun-breech. (Shown in Fig. 4.) The end of the crank A moves in a cam-slot in the block so that when the shaft is rotated the block is moved to unmask the gun-bore or close the same. The extractor E' is provided with a lug E", which moves in an extractor-slot formed in the breech-block. As the block moves downwardly the extractor is drawn rearwardly, removing the empty cartridge-case from the gun when the downward movement of the block is sufficient to unmask the bore. A crank-handle is provided for rotating shaft B, said handle carrying a cocking-cam, which engages a cocking-toe, and the first movement of said crank-handle effects the cocking of the hammer.

In the application of my invention to a gun provided with the breech mechanism above set forth the crank-handle for shaft B and the cocking-cam operated thereby are removed, and upon said shaft on the exterior of the breech I key an arm which is in the form of a cylinder C, said cylinder being formed about the upper portion of its periphery with a flange D, in which a concentric slot E is formed, having an enlargement F at its forward end. A stud G is screwed into the exterior of the breech and extends into said chamber, a concentric slot G' being formed in the wall of the latter, so that its rotation is not impeded by the stud. Within cylinder C is a spiral

or what is known as a "clock-spring" H, one end of said spring being screwed to the stud, and its opposite end attached to the cylinder. Loose upon shaft C is a short arm I, to which 5 one end of a rearwardly-extending arm or lever J is pivotally connected. The opposite end of said arm J is pivoted to an attaching-plate J', screwed to some convenient part of the mount. Arm I is formed on its free end 10 beyond its pivotal connection with arm J with a casing I', containing a revolving locking member k, having an elongated toe k', adapted to move in said concentric slot E of cylinder C. A spring h in said casing has a tendency 15 to revolve said locking member until toe k extends transversely of the slot. This rotation of the locking member, however, is prevented by the engagement of the toe with the walls of said slot. When the gun recoils, 20 the outer end of arm I is drawn forwardly through the medium of its pivotal connection with arm or lever J, the toe of the locking member moving in slot E of the cylinder. When the toe of said locking member reaches 25 the enlarged end of slot E, it is turned to extend transversely thereof by a spring h, said enlargement being sufficient to permit such rotation of the locking member, thus locking the arm and cylinder together. The gun having 30 reached the limit of its recoil, the parts have assumed the positions as illustrated in Fig. 2. Upon the return of the gun to the battery arm I is returned to its original position, carrying with it the cylinder and winding the spring therein. The rotation of the 35 cylinder, which is keyed to the operating-shaft B, rocks said shaft and effects the downward movement of the breech-block to open the breech.

40 Fig. 3 clearly illustrates the positions of the various parts when the breech has been opened and the gun ready for loading. The cylinder is held in the position shown in Fig. 3, and the block in its lowered position by 45 the abutting of the toe of the locking member against the end wall of the enlargement of slot E. The locking member has an arm i, to which a tripping-cord j is attached, and when a fresh cartridge has been placed in the 50 gun the breech may be closed by drawing upon said cord, which revolves the locking member, bringing the toe thereof in line with the concentric slot, so that the cylinder may be returned to its normal position by its 55 spring. The cylinder is formed with the cocking-cam L, which engages the usual cocking-toe used in the Hotchkiss mechanism, so that the movement of the cylinder effects the cocking of the hammer. Said cylinder is 60 also provided with a handle M for the purpose of effecting the opening of the breech by hand at the beginning of the firing and also for the purpose of operating the breech-block by hand should the mechanism become injured and not operate effectively.

65 In the modified construction, illustrated

by Figs. 7 to 13, inclusive, the cylinder and arm I are constructed similarly to the construction just described, with the exception that an inwardly-pressed spring-plunger K 70 is provided instead of the revolving locking member, and instead of the enlarged forward end of the concentric slot in flange of the cylinder a countersink is made, forming the seat 75 for the larger portion of the plunger. The plunger has a reduced outer end m, which moves in slot E of the cylinder. A false extractor n moves in a groove in the breech, and a spring o tends to normally press the same rearwardly, as illustrated in Fig. 8. 80 When, however, a cartridge is in position in the gun, this extractor is in the position illustrated by dotted lines in said figure and is held in the position by the cartridge against the tension of its spring. The wall of the 85 gun-breech is formed with a chamber p extending transversely therethrough, and in this chamber a tripping-bolt q is positioned. This tripping-bolt has an inclined or cam inner end r, which has a tendency to normally 90 project into the interior of the breech-housing, owing to the pressure of a spring s, but is prevented from so doing by the false extractor when the latter is in its forward position. The outer end of said bolt is therefore 95 projected from the breech and into the concentric slot of the spring-cylinder. The false extractor is formed with a slot t, having an inclined or cam end wall t'. When the gun recoils, the outer end of arm I moves forwardly, the reduced portion of the plunger carried by said arm moving in the concentric slot of the cylinder until the countersink is 100 reached, when the enlarged portion of said plunger is forced thereinto by its spring. As 105 the gun returns to battery arm I moves in its original position, carrying with it the cylinder and winding the spring therein. The breech-block is thus moved to unmask the bore of the gun. In the meantime the true 110 extractor has extracted the cartridge-case and the false extractor has been forced rearwardly by its spring, bringing its slot into position to receive the inner end of the tripping-bolt, which is caused to enter said slot by its 115 spring. The parts have now assumed the positions illustrated in Figs. 8 and 10. The device is tripped to close the breech by inserting a cartridge and pressing the same forwardly until the false extractor has been 120 moved far enough to press the tripping-bolt outwardly, which it does through the engagement of the cam-wall of its slot with the cam end of the bolt. The inner end of said bolt engages the reduced portion of the locking-plunger and as the bolt is moved outwardly 125 forces the plunger from the countersink, as illustrated in Fig. 11. There being thus no obstruction to the independent rotation of the cylinder, it is rotated to its original position 130 by the unwinding of its spring and the breech-block moved to close the breech.

Having thus fully described my invention, what I claim, and desire to secure by Letters Patent of the United States, is—

1. The combination with a breech-loading gun, a recoil-mount, and a breech-block, of an arm pivoted to the gun, an arm carried by a non-recoiling part of the mount and having an operative connection with said first-mentioned arm, and means for operatively connecting said first-mentioned arm with the block on counter-recoil of the gun, substantially as described.

2. The combination with a breech-loading gun, a recoil-mount, and a breech-block, of an arm pivoted to the gun, an arm pivoted to a non-recoiling part of the mount and having an operative connection with said pivoted arm, means for operatively connecting said first-mentioned arm with the block on counter-recoil of the gun, and means for disconnecting said arm from said block, substantially as described.

3. The combination with a breech-loading gun, a recoil-mount, and a breech-block, of an arm pivoted to the gun, an arm pivoted to a non-recoiling part of the mount and having an operative connection with said first-mentioned arm, means for operatively connecting said first-mentioned arm with the block on counter-recoil of the gun, a spring placed under tension by said arm, and means for disconnecting said arm from said block to permit the latter to be closed by the spring, substantially as shown and described.

4. The combination with a breech-loading gun, a recoil-mount, a breech-block, and a rock-shaft for actuating said block, an arm loose on said shaft, an arm pivoted to a non-recoiling part of the mount and having an operative connection with said first-mentioned arm, and means for automatically locking said first-mentioned arm to the shaft on counter-recoil of the gun, substantially as described.

5. The combination with a breech-loading gun, a recoil-mount, a breech-block, and a rock-shaft for actuating said block, an arm loose on said shaft, an arm pivoted to a non-recoiling part of the mount and having an operative connection with said first-mentioned arm, means for automatically locking said first-mentioned arm to the shaft on counter-recoil of the gun, and means for releasing said arm from said shaft, substantially as described.

6. The combination with a breech-loading gun, a recoil-mount, and a breech-block, of an arm pivoted to the gun, an arm pivoted to the mount and having an operative con-

nexion with said first-mentioned arm, means for operatively connecting said first-mentioned arm with the block on counter-recoil of the gun, a spring placed under tension by said arm, and means for automatically releasing said first-mentioned arm from the block when a fresh cartridge is inserted in the gun, substantially as described.

7. The combination with a breech-loading gun, a recoil-mount, and a breech-block, of an arm pivoted to the gun and movable relatively to the block, means for preventing such relative movement of the arm on counter-recoil of the gun, and an arm carried by a non-recoiling part of the mount and operatively connected with said pivoted arm, substantially as described.

8. The combination with a breech-loading gun, a recoil-mount, and a breech-block, of an arm pivoted to the gun and movable relatively to the block, means for preventing such relative movement of the arm on counter-recoil of the gun, means for releasing said arm, an arm carried by a non-recoiling part of the mount and operatively connected with said pivoted arm, and means for moving the block to its closed position, substantially as described.

9. The combination with a breech-loading gun, a recoil-mount, a breech-block, and a rock-shaft actuating the block, of an arm fixed on said shaft, an arm loose on said shaft, locking means for locking said arms together on counter-recoil of the gun, an arm carried by a non-recoiling part of the mount and pivoted to said loose arm, a spring connected to the gun and to said fixed arm, and a tripping device for operating said locking means to release the fixed arm from the loose arm, substantially as described.

10. The combination with a breech-loading gun, a recoil-mount, a breech-block, and a rock-shaft actuating the block, of an arm fixed on said shaft, an arm loose on said shaft, locking means for locking said arms together on counter-recoil of the gun, an arm carried by a non-recoiling part of the mount and pivoted to said loose arm, a spring connected to the gun and to said fixed arm, and a sliding extractor adapted to operate said locking device to release the fixed arm from the loose arm, substantially as described.

In testimony whereof I affix my signature in presence of two witnesses.

WILLIAM H. BEVANS.
